UNITED STATES PATENT OFFICE.

ROBERT SOYER, OF ISSY, FRANCE.

IGNITER FOR INTERNAL-COMBUSTION ENGINES.

1,409,887.

Specification of Letters Patent. Patented Mar. 14, 1922.

Application filed May 27, 1919. Serial No. 300,200.

(GRANTED UNDER THE PROVISIONS OF THE ACT OF MARCH 3, 1921, 41 STAT. L., 1313.)

To all whom it may concern:

Be it known that I, ROBERT SOYER, a citizen of the Republic of France, residing at 179 Quai d'Issy, Issy, Seine, France, have invented certain new and useful Improvements in Igniters for Internal-Combustion Engines, of which the following is a specification.

This invention has for its object to provide igniters for internal combustion engines, which igniters can be readily removed and replaced, they being especially intended to be employed in connection with engines, of great power in which high compression, is used; such, for example, as in the engines used with air-craft.

Igniters as hitherto constructed and applied have many drawbacks and such of them as have certain good qualities, usually have also serious defects. For example, in devices with compact insulators, it has been necessary to employ joints made by metallocplastic or amianthus, or cement, silicate, and the like, which joints are not always tight, especially after the first cleaning, and in some cases their removal, and taking to pieces, are rendered impossible.

In igniters which are removable from the outside, making the joints as usual by agglomeration (on what is known as the Schopp system), or by moulding, or by means of soft metal, will not avoid leakage between the insulator and its cover. The cone joints employed in some cases, necessitate knocking in order to disconnect the apparatus, and this usually injures the insulators.

The igniter made in accordance with the present invention, has none of the aforesaid drawbacks, but has all the advantages which are so desirable in the kind of igniter to which this invention relates my improved igniter being provided with a rigid metal sleeve encircling the insulator and perfectly fitting and adhering to it under working temperature, this arrangement superseding all joints in the igniter and assuring at all times the requisite tightness, whilst enabling the igniter to be at once withdrawn from the exterior for cleaning, or repair. The igniter is also provided with compressible discs which prevent expansion of the parts under heat from altering the pressure on the insu-

lator. The protecting cap, or insulator cover, of the upper, or outer, part of the igniter merely acts as a protecting piece which is hermetically closed, but can be readily removed without interfering with the igniter itself, and the electrode which is adjacent to that carried by the central rod acts as a guard against the entrance of dust, or the fall of debris into the cylinder in case of breakage.

The accompanying drawing illustrates an igniter constructed in accordance with this invention, Figure 1 is a longitudinal section Figure 2 shews the igniter removed for cleaning, or repair Figure 3 is an underside end-view. Figure 4 is a cross sectional view of a portion of the igniter showing the sleeve and insulated portion, on an enlarged scale.

The electrode, is constituted by a screwed conducting rod *a*, and the lower end piece *b*, (which is preferably of pure nickel), which constitutes the electrode point. The said rod *a* is embedded in a compact insulator *c* which may be of porcelain, steatite or the like, and whose exterior has a slight inclination, so as to constitute a suitable bearing for the sleeve *d* which surrounds it and constitutes the sole joint of the whole igniter. It is of hard, rigid, material, preferably steel, and is properly fashioned and then permanently mounted on the insulator its inner surface having an inclination the same as that of the opposed surface of the insulator the inclination of these two surfaces being determined so that the different expansibility of the two bodies, will give perfect tightness of the joint at working temperatures.

The sleeve *d* is secured by the screw-nut *e* in the socket-piece *f* carried by the engine, the screw-nut *e* forcing the flange *d*² on the sleeve *d* against the ledge *h*³ on the said socket-piece *f* the said sleeve being guided in the seat *g* of the said socket-piece *f*, by a shoulder *h*, reducing to a minimum the surface of contact of the heat conducting surfaces.

The lower end of the socket-piece has fixed in it a shield *i*, which may be, say, of steel, or nickel; its outer side being concave and its centre being perforated. This shield *i* constitutes the annular electrode, and is also a protector against the admission of dirt and also affords absolute security

against the descent of debris from the parts above into the engine cylinder, in the event of breakage.

The rod *a* is fastened to the insulator *c*, but it carries several discs *k*, preferably of pure copper, which are placed between the upper, or outer, end of the insulator *c* and a nut *k²* screwed onto the rod *a*, and between the other end of the insulator *c* and the back 10 of the electrode point *b* and compensate for expansion and contraction and cause the pressure to be constant at working temperatures.

The upper end of the rod *a* has the securing screw-nut *l*, screwed onto it to hold the protecting-cap, or insulating hood, *p* (of any suitable insulating material) in place, the said cap, or hood, bearing, at its lower part, on the screw-nut *e* as shown; so that the 15 cap, or hood, *p*, is not a fixture but can be readily removed and comes away with the other parts of the igniter when dismounted whilst it affords a perfectly hermetical joint and excludes oil, dust, and water, which are 20 usually, in ordinary igniters such fruitful sources of short circuits.

The sleeve *d* is adjusted to the insulator *c* in such a way as to adhere perfectly to it at the operating temperature. In practice this 30 adjustment takes place after having turned the insulator to a cone of about 0.142°, (Fig. 4) and fitting on the ring which has been turned to the same cone, having previously heated it in hot oil. This adjustment taking 35 place under a pressure of about 600 kg., and at a temperature slightly above the operating temperature, that is to say 400 degrees. The ring then adheres absolutely to the insulator and forms a part of it. This relatively 40 slightly conical shape is chosen in order to assure the tightness of the insulator to the ring, assuring its closing during the operation of the motor and at the same time the cone is sufficiently slight to obtain al- 45 most a cylindrical form so that as the con-

traction of the ring forms a ferrule, the pressure of the mounting is released uniformly, and on a porcelain body maintaining perceptibly the same thickness throughout.

As seen from Figure 2, the whole of the parts constituting the igniter can be removed together from the cylinder, the igniter which can remain attached to the conductor *m*, avoiding the removal of the socket-piece *f* 50 and rendering cleaning very easy.

It will be understood that this invention is not limited to the precise details of construction illustrated as they can obviously be varied in accordance with the requirements 60 of any particular case.

The insulators, can be made of any suitable substance, such, for instance, as porcelain, crystal quartz, steatite, and the like.

Having now particularly described and 65 ascertained the nature of my said invention and in what manner the same is to be performed, I declare that what I claim is:—

1. In igniters for internal combustion engines, a sleeve of rigid metal, with an inclined interior and adapted to an insulator with a correspondingly inclined exterior, the insulator surrounding a central rod carrying the electrode point, the said sleeve having a rigid metal shoulder, and being held 70 in the igniter socket-piece by a screw-nut holding said shoulder on the sleeve against a ledge in the socket-piece; substantially as hereinbefore explained.

2. In an igniter in accordance with the 80 preceding claiming clause; the combination of copper, or like, discs arranged as described, so as to compensate for expansion and contraction between the insulator and the rod of the electrode; substantially as 85 hereinbefore explained.

In witness whereof, I have hereunto signed my name.

ROBERT SOYER.
